UNITED STATES PATENT OFFICE

JOHN BRUNNEE, OF CHICAGO, ILLINOIS

RAIL JOINT

Application filed June 12, 1930. Serial No. 460,669.

This invention relates to tie plates for railway tracks and has for an important object thereof the provision of a novel and improved tie plate for holding a rail section in firm engagement with a tie.

The invention relates, not so much to the shape of the tie plate as it does to the co-operation of the means and the method of binding the rail section, the tie plate, and the tie against movement relatively to each other.

Additional objects and features of the invention will be brought forth from a reading of the following specification in the light of the accompanying drawing, in which—

Figure 1 is a plan view showing a segment of rail section passing over two ties and secured thereto in accordance with the present invention;

Figure 2 is a view in side elevation of the assemblage shown in Figure 1; and

Figure 3 is a view in end elevation of the same.

Turning now to the drawing, the reference numeral 10 indicates a rail section and the reference numerals 12 and 14 designate the customary railway ties for supporting the rail section. As more clearly shown in Figure 3 a tie plate 16 is interposed between the base flange of the rail section and the upper surface of the tie.

Heretofore the usual practice has been to secure the base flange of the rail to the tie plate by means of headed spikes driven into the fiber of the tie, or by lugs extending through the plate and bolted on the under side thereof. The present invention improves upon these old methods of securing the assemblage by providing fasteners extending completely through the tie for exerting binding pressure upon the base flanges of the rail section and the under surface of the tie. As shown, the fasteners

may take the form of headed bolts 18, pro-

vided with elliptical shank portions 20 tending to prevent rotation. To strengthen the assemblage there may be provided a washer plate 22, or a plurality of washers, for disposal on the undersurface of the tie. If made of a single piece the washer plate may be provided with elliptical openings to co-operate with the shank portions 20 of the bolts, thereby preventing rotation of the latter.

The tie plate 16 is provided with the customary positioning shoulders 24 for engaging the outer edges of the base flanges of the rail section and in accordance with the present invention the tie plate is also provided with transversely extending ribs forming the grooves 26 for receiving the outer turned down ends of clamping shoes 28. Bolts 30 complete the assemblage.

In operation the rail section rests snugly between the oppositely disposed shoulders 24, 24 and is held firmly against vertical displacement by means of the clamping shoes 28, 28, engaging the opposite upper surfaces of the base flanges. The shoes, of course, are held rigidly and permanently in position by means of the fasteners 18.

Numerous advantages are to be gained from the illustrated type of construction, one of the outstanding of which results from the facility with which the clamping elements may be removed to permit replacement of a worn rail section or tie plate. By removing the nuts 30 from the fasteners 18 the parts may be disassembled to permit removal of the clamping shoes 28, whereupon the rail section is no longer clamped.

It is to be understood that the fasteners 18 may possibly take the form of screw bolts threaded into the tie or of headed spikes, and that in such instance the invention resides in the combination with such fasteners of the clamping shoe and grooved tie plate.

Although the invention has been described

herein with particular reference to one specific embodiment thereof, it is to be appreciated, of course, that certain changes and modifications and alterations may be made 5 in the illustrated form without departing from the scope of invention as outlined in the appended claims.

Having thus described my invention, what I claim is new and desire to secure by United 10 States Letters Patent, is:

1. An assemblage of the character described comprising, in combination, a tie, a rail section, a tie plate, and means for holding the rail section in rigid engagement 15 with the tie plate, said means including a plurality of spaced transverse ribs provided on said tie plate to each side of the rail respectively, and clamping shoes, certain of said ribs forming positioning shoulders for 20 the base flange of the rail section, the others providing a groove on each side of the rail for receiving a portion of the clamping shoe to position the same, said shoe engaging the base flange of the rail, and a fastener extending completely through the clamping 25 shoe, tie plate and tie for securing the clamping shoe.

2. An assemblage of the character described comprising, in combination, a tie, a 30 rail section, a tie plate, and means for holding the rail section in rigid engagement with the tie plate, said means including a plurality of spaced transverse ribs provided on said tie plate to each side of the rail respectively, and clamping shoes, certain of 35 said ribs forming positioning shoulders for the base flange of the rail section, the others providing a groove on each side of the rail for receiving a depending portion on the 40 clamping shoe to position the same, the horizontal body portion of said clamping shoe being adapted to extend over the base flange of the rail section, and fasteners for securing the clamping shoe to the tie plate, said 45 fasteners having a portion engaging the lower surface of the tie, and removable locking means located above the clamping shoes.

Signed at Chicago, Illinois, this 7 day of 50 June, 1930.

JOHN BRUNNER.
